(57) **CLAIM**

The ornamental design for an electronic display, as shown and described.

DESCRIPTION

FIG. 1 is a rear elevation view of the electronic display of the present disclosure;

FIG. 2 is a side elevation view of the electronic display of the present disclosure, the opposite side elevation view being a mirror image of FIG. 2;

FIG. 3 is a top plan view of the electronic display of the present disclosure;

FIG. 4 is a front elevational view of the electronic display of the present disclosure;

FIG. 5 is a bottom plan view of the electronic display according to an embodiment of the present disclosure;

FIG. 6 is a front perspective view of the electronic display of the present disclosure; and,

FIG. 7 is a rear perspective view of the electronic display of the present disclosure.
